SURFACE ORNAMENTATION

Stephen J. Heinrich, Newton Highlands, Mass.

Application August 13, 1929, Serial No. 385,566

2 Claims. (Cl. 41—21)

This invention relates to the ornamentation of lacquered surfaces and particularly to the striping of surfaces covered with a lacquer consisting essentially of a cellulose ester, as the lacquer known in the trade as "duco".

It is common to paint a distinctively-colored narrow band or ribbon on the lacquered surface of an automobile, an article of furniture, and the like for the purpose of ornamentation.

When the surface coating consists of a cellulose lacquer, a stripe of the same material can not be applied successfully to the surface because the material softens or dissolves the surface coating and causes the stripe to run so that the desired sharp line of the stripe is destroyed. Consequently, the striping material is usually an ordinary paint or a resin lacquer consisting of a relatively large amount of pigment and a small amount of binder. The stripe has not proven satisfactory, however, as it is not as durable as the surface lacquer and soon wears off, due to washing, polishing and other abrading forces.

It is an object of the present invention to provide a striping material which is adapted to be applied to a lacquer surface, and especially a surface covered with a cellulose lacquer, and which is much more durable than any striping material heretofore employed and has such characteristics that it adheres strongly to the lacquered surface and does not run thereon.

Striping is an art that requires considerable skill which is attained only by long practice and, consequently, is expensive.

It is a further object of the invention to provide a method of and materials for striping, such that the striping can be applied quickly and satisfactorily by one who has had little previous experience in striping.

It is another object of the invention to provide a method of and material for striping by which ornamental designs that heretofore have been beyond the skill of the usual stiper or have been prohibitive by reason of expense can be cheaply and easily applied to a surface.

In carrying out the invention, I provide a striping material which instead of being a liquid paint or lacquer as heretofore, is in the form of a long and thin solid ribbon or web; and such ribbon or web constitutes the stripe. The ribbon is of suitable thickness and width and of the desired configuration. It may, for instance, be narrow and have parallel side edges if the stripe is to be a "hair-line" stripe or it may be a broader ribbon, or have serrated or scalloped

edges, or be otherwise formed. It can also be composed of various colors. Such a striping material constitutes a further object of the invention.

The striping ribbon is capable of being softened by the application of a suitable solvent thereto and of then adhering permanently to the lacquered surface to which it is applied. Such ribbon and the manner of applying it constitutes a further object of the invention.

Fig. 1 represents, in plan view, a portion of a hair-line striping ribbon embodying the invention.

Fig. 2 is an enlarged cross section taken along line 2—2 of Fig. 1.

Fig. 3 is a section similar to Fig. 2 but illustrating a modified construction of the ribbon.

Fig. 4 is a cross section illustrating the striping ribbon adherently united to a lacquered surface.

Fig. 5 is an elevation of a drum by means of which the ribbon of Figs 1 and 2 is made.

Fig. 6 is an enlarged sectional view of the periphery of the drum of Fig. 5, taken along line 6—6 of Fig. 5.

Fig. 7 is a view similar to Fig. 6, with the striping material applied thereto.

Fig. 8 is a view similar to Fig. 7 but with the ribbon in readiness to be removed from the drum.

Fig. 9 is a view similar to Fig. 6 but illustrating a modified manner of forming the stripes.

Figs. 10 and 11 are plan views of striping ribbons of different types, all embodying the present invention.

In accordance with the present invention, the stripe, or the ribbon which composes the stripe, preferably is formed or cut from a large sheet of striping material and Figures 5 through 8 illustrate various steps in the manufacture of the stripe.

The ribbon consists of a pigment and a binder therefor. The pigment can be any thing desired. It can be ground in japan or other vehicle. It can be any suitable color. A dye can be used instead of a pigment. The binder is preferably of a colloidal nature and is capable of being soluble or softenable in a suitable solvent or softening agent. Preferably the binder is a cellulose ester as a cellulose nitrate or acetate and may or may not be associated with a metallic salt. Preferably it is the same material as that which composes the coating to which the striping ribbon is to be applied. If the coating is "duco" the

binder ordinarily will consist of cellulose nitrate or acetate. The stripping material initially is in liquid form which is applied, preferably as a spray, to and hardens in sheet form on a surface 5 from which the striping ribbon is subsequently removed. The liquid consists of the binder and its solvent and the pigment or dye. If the binder is cellulose nitrate, for instance, the solution can be made up of six ounces of nitro-cellulose to one gallon of a volatile solvent, as acetone. The proportions of pigment to the solution will vary with the color of the pigment. I find that two per cent by volume of black pigment and ten per cent of white pigment gives good results. 10 Obviously, there is no critical proportion and the amount used will depend upon the color and the requirements. The above proportions of binder to solvent give good results but can be varied, also. If desired, a metallic salt can be added to 15 the cellulose solvent, as is now well known, to increase the percentage of binder capable of being contained in the solvent without causing the solution to be unworkably viscous. The liquid may be replaced by a dye as is now common in 20 the art of making cellulose lacquers. If desired, although not essential, a suitable filler may be added to the solution when a dye is used. A plasticizing agent, as glycerin, or castor oil or the like, can be added to the solution so that the 25 resultant striping ribbon will be flexible and not so brittle as to break under the ordinary handling it receives in manufacture and in applying it to the surface.

The ribbon-forming material has such characteristics that the ribbon made therefrom is rapidly softened or made plastic by the application of a solvent and is then capable of adherently uniting permanently with the surface to which it is applied. Preferably, the solvent is also a 30 solvent for the surface coating so that the coating under the ribbon is also softened and rendered adhesive, so that both are firmly bonded together when the solvent has evaporated, and the ribbon has hardened.

45 The liquid striping material is formed into solid sheets preferably by spraying the material onto a suitable surface and allowing the coating to harden and form a solid sheet or film of suitable thickness thereon. Striping ribbons of suitable dimensions and configuration are subsequently cut or formed from such sheets.

50 Preferably the liquid material is sprayed onto the surface of a cylindrical metal drum to form a film from which the ribbon is subsequently made.

55 Figs. 5 and 6 illustrate a suitable drum 16 which has a spiral groove 18 cut in its periphery to form a number of contiguous convolutions. The groove preferably is circular in cross section 60 as illustrated in Fig. 6, and the convolutions are separated by a sharp spiral ridge 22. The striping material is sprayed uniformly upon the periphery of the drum and in the convolutions of the groove and upon the sharp ridge to form a solid film 24 having a suitable thickness, as two or three thousandths of an inch, as in Fig. 7. The depth of the groove preferably is greater than the thickness of the film. The material overlying the ridge is then removed either by a 65 suitable cutting or abrading device or by the application of a solvent for the material, thereby to expose the ridge 24 and thus separate the material in the consecutive convolutions, thereby to form a long ribbon 26 which occupies the groove 70 and the convolutions of which are separate. The

ribbon is then unwound or stripped from the drum and is wound into a roll or otherwise packaged so that it can be applied in a convenient manner to lacquered surfaces. As thus made, the striping ribbon 26 is formed with a convex outer surface 28, see Fig. 2, and a concave inner surface 30. The opposed bottom edges 32 are flat and the side edges 34 are acute with respect to the bottom faces 32 so that when the ribbon is applied to the lacquered surface, it will adhere firmly thereto without presenting abrupt surfaces that might be torn off. 5

In applying the ribbon to the lacquered surface, one end of a suitably long length of the ribbon is treated with a solvent for the binder 15 in any suitable manner as by brushing a little of the solvent upon the bottom face of the ribbon. The solvent immediately softens the binder and renders it adhesive. The softened end of the ribbon is pressed onto the lacquered surface into 20 the desired position and held there for a short time or until the moistened end of the ribbon adheres to the surface. A suitable length of the ribbon is then extended upon the surface in the desired location and while held in position while 25 a solvent is applied thereto, preferably upon its top face by a brush or atomizer. The solvent immediately penetrates the ribbon and softens the binder which unites with the lacquered surface and hardens thereon and becomes an intimate and integral part thereof, so that it is 30 permanently attached to the surface. The softened ribbon becomes plastic so that it in effect beds down upon and, to some extent, into the lacquered surface so that it unites permanently 35 therewith, yet without running or spreading on the surface.

Fig. 4 illustrates in cross section the disposition of the ribbon after it has been applied to the lacquered surface *a*. The concave portion 40 30 of the ribbon usually disappears and the side edges of the ribbon sink into the lacquered surface so that the edges of the ribbon merge smoothly and in a well defined line with the surface without presenting sharp exposed edges 45 that can be raised and torn away.

The ribbon is, or can be, as thick or thicker than the surface of the lacquer to which it is applied so that it will wear equally well with the lacquer and can withstand any usual wear thereon without disintegrating. 50

While it is not absolutely essential, it is highly desirable to provide the ribbon with the bevelled or acute edges 34 so that the striping ribbon when united with the lacquered surface, will not 55 present any sharp or projecting parts. Instead of constructing the ribbon as above described, it can be made by applying a coat of striping material onto the smooth and ungrooved periphery of a drum 16a, see Fig. 9, to form a smooth uniform 60 sheet or film 28a thereon. Ribbons 28b of suitable width can be cut from said sheet by a cutting tool 36 having a V-shaped cutting edge which is fed in a uniform manner, similar to cutting a screw-thread, from one end to the 65 other of the cylinder and cut through the sheet down to the periphery of the cylinder, thereby separating the sheet into the aforesaid ribbon. By the use of the V-shaped cutting tool, the ribbon is provided with bevelled side edges 38, the 70 effect and advantages of which are the same as that resulting from the convex configuration of the ribbon 26.

The striping ribbon can have any suitable width. It can be made much narrower than any 75

stripe which can be applied commercially with a brush. Striping ribbons only seven or eight thousandths of an inch have been made and applied successfully to lacquered surfaces in the 5 manner above described. Even narrower striping ribbons can be used, if desired. The difficulty of applying such narrow stripes by a brush will be apparent.

The striping ribbon can have parallel side 10 edges as shown in Figs. 1, 2 and 3, or it can have other configurations as illustrated in Figs. 10 and 11 and can be perforated as at 40 in these figures. Such ribbons as are shown in Figs. 10 and 11 are formed by running a sheet of the 15 material between suitably-formed cutting wheels as, for instance, by applying a suitably formed knurling wheel to the sheet 28a on the drum 16a.

Striping a surface by the striping ribbon herein described can be accomplished by a relatively 20 inexperienced person since the ribbon can be extended upon the surface and moved about until the desired position is obtained and then held in such position while the solvent is applied

and until the softened ribbon is adherently united with the surface. The ribbon is of fixed and unchanging width so that the skill heretofore involved in the manipulation of the striping brush is not necessary.

Ornamental stripes such as shown in Figs. 10 and 11 can be applied to the surface as readily as the plain ribbon of Fig. 1, thus to impart to the surface an ornamental appearance that can not be attained by the use of a brush except at 10 a prohibitive expense. Stripes of various combinations of colors can also be readily applied which would not be commercially practicable by heretofore known methods.

I claim:

1. Striping material consisting of a soluble ribbon having a convex upper face and a bottom face which is flat at least in part. 15
2. Striping material consisting of a soluble ribbon having a convex upper face and a bottom 20 face that is flat at the side edges and is concave in the middle.

STEPHEN J. HEINRICH.
